US0D1043301S

(12) **United States Design Patent** (10) **Patent No.:** **US D1,043,301 S**
Jackson, II et al. (45) **Date of Patent:** **** Sep. 24, 2024**

(54) **APPARATUS FOR PARTITIONING CONSTRUCTION MATERIALS**

(71) Applicant: **Westlake Royal Building Products Inc.**, Houston, TX (US)

(72) Inventors: **William E. Jackson, II**, Portland, OR (US); **Jacob Myers**, Corona, CA (US); **Russell L. Hill**, San Antonio, TX (US); **Amitabha Kumar**, San Antonio, TX (US); **Russ K. Majors**, San Marcos, TX (US); **Daniel Genord**, South Lyon, MI (US); **Grey Parker**, West Bloomfield, MI (US)

(73) Assignee: **Westlake Royal Building Products Inc.**, Houston, TX (US)

(**) Term: **15 Years**

(21) Appl. No.: **29/722,711**

(22) Filed: **Jan. 31, 2020**

(51) LOC (14) Cl. **08-05**

(52) U.S. Cl.

USPC **D8/71**; D15/122

(57) **CLAIM**

The ornamental design for an apparatus for partitioning construction materials, as shown as described.

DESCRIPTION

FIG. 1 is a front perspective view of the apparatus for partitioning construction materials;

FIG. 2 is a side perspective view thereof;

FIG. 3 is a back perspective view thereof;

FIG. 4 is a front view thereof;

FIG. 5 is a right side view thereof; and,

FIG. 6 is a top view thereof.

The broken lines in the drawings represent environmental structure or boundaries that form no part of the claimed design. The left side view of the apparatus is a mirror image of the right side view shown in FIG. 5.

1 Claim, 6 Drawing Sheets
